UNITED STATES PATENT OFFICE.

FRANZ A. BARTELMEZ, OF NEW YORK, N. Y.

CARBON-SHEET HOLDER.

SPECIFICATION forming part of Letters Patent No. 660,142, dated October 23, 1900.

Application filed June 25, 1900. Serial No. 21,452. (No model.)

To all whom it may concern:

Be it known that I, FRANZ A. BARTELMEZ, a citizen of the United States, residing in the city, county, and State of New York, have invented certain new and useful Improvements in Carbon-Sheet Holders, of which the following is a specification sufficient to enable others skilled in the art to which the invention appertains to make and use the same.

10 My invention relates to holders for carbon-sheets to be used in transferring copy to the page of a book or equivalent.

The object of the invention is to afford a comparatively simple, cheap, and effective device that may be discarded with the carbon-sheet to which it is attached when it is desired to replace the latter with a fresh carbon-sheet having its own holder. In other words, each carbon-sheet is attached to an individual holder of such economical construction that it may be thrown away with the exhausted sheet, thereby avoiding the inconvenience and discomfort of attaching a fresh carbon-sheet to a holder from time to time, 25 as heretofore required.

The invention consists in the special form and construction of parts attached to a carbon transfer-sheet and hereinafter more fully described and claimed.

30 In the accompanying drawings, Figure 1 is a blank representing my improved carbon-sheet holder before it is folded upon itself. Fig. 2 is a top view of the holder folded. Fig. 3 is a view of the under side of the holder; Fig. 4, a transverse section, upon an enlarged scale, upon plane of line 4-4, Fig. 3, showing the holder folded, with the carbon-sheet and protecting-sheet attached to a coupling-strip. Fig. 5 is a view similar to Fig. 4, showing the 35 holder open. Fig. 6 is a view similar to Fig. 4, showing an edge of a sheet of paper clamped in the holder, the carbon-sheet being in this case attached directly to the holder. Fig. 7 is an isometrical view of the holder open; Fig. 8, a view of the under side of the holder, showing the method of attaching the carbon-sheet and protecting-sheet; Fig. 9, an isometrical view of the holder with carbon-sheet and protecting-sheet attached; Fig. 10, an 40 isometrical view illustrating the practical use of the holder. Fig. 11 is a plan of a modified form of holder.

In carrying out my invention I prefer to make the holder of a single piece or blank A, Fig. 1, of comparatively inexpensive material—as cardboard, stiff paper, or other fibrous material—although the device may obviously be made of metal or other relatively-costly material if preferred or designed for permanent use in connection with a succession of 55 carbon-sheets. By making the holder of paper, cardboard, &c., it can be discarded with the depleted carbon-sheet to which it is attached, and of which it forms a part as an article of manufacture and trade. 60

The holder H consists of the lower plate or base h, to which one edge of the carbon-sheet c and one edge of the protector-sheet p are attached, either directly or indirectly. Thus instead of attaching the carbon-sheet c 65 and protecting-sheet p directly to the base h, as shown in Figs. 6 and 9, I prefer to interpose a coupling-strip s, of paper or other flexible material, said strip s being secured to the base h at one edge and overlapping 70 the same sufficiently to afford a margin s', to which an edge of the carbon-sheet c and an edge of the protecting-sheet p may be separately attached, as illustrated in Figs. 4, 5, and 8. The edge of the intermediate strip s 75 being attached to the upper side of the base h, the edges of the carbon-sheet and protecting-sheet are gummed to the under side of said strip s, the edge p' of the protecting-sheet p being attached above the edge c' of 80 the carbon-sheet c, so that the protecting-sheet p may be stripped off without disturbing the carbon-sheet when the latter is desired for use, as indicated in Fig. 8. The strip s being of stronger texture than the 85 carbon-sheet by its flexibility relieves the latter from undue strain in adapting itself to the requirements of use, it being obvious that a rigid connection between the comparatively thin fragile paper and the substantially rigid plate h is undesirable, although this direct connection of the carbon-sheet 90 may be resorted to without departing from the spirit and intent of my invention and as indicated in Figs. 6 and 9. 95

The clip h' for holding the sheet W to be written upon is formed directly from the plate h by cutting or stamping its front and sides out of the body thereof, the rear portion of 100

the clip h' remaining attached to the plate h . One or more of these clips may be used, although I prefer the use of a single clip h' , as shown in the drawings, situated centrally and 5 extending the greater portion of the length of the base-plate h . In most of the drawings the rear portion is shown as bent over to form a fold h^2 , which may be pressed down upon the clip h' and paper W introduced 10 thereunder, as shown. This plate h is preferably formed with rearwardly-projecting tongues t for engagement with and between the copy-sheets b in proximity to the line of binding, as b' , in the case of copying book 15 or pad B , as shown in Fig. 10. These projecting tongues t may be formed in one piece with the blank A , as indicated in Fig. 1, and then folded over and secured in position, or they may be separately formed and attached 20 to the under side of the plate h , as may be found most expedient.

In use when a fresh carbon-sheet is desired the protection-sheet p is pulled off, as indicated in Fig. 8, one edge of a sheet of writing-paper W inserted under the clip h' , and the holder forced between the copy-sheets at the binding end, those sheets b above being folded over out of the way to leave the writing-sheets unobstructed. The act of forcing 25 the holder between the sheets b forces the clip h' down against the edge of the paper W , so that the latter is pinched and the sheet held against displacement. The withdrawal 30 of the holder releases the sheet w .

35 What I claim as my invention, and desire to secure by Letters Patent, is—

1. As an article of manufacture a copying device consisting of a strip of stiff material having a paper-retaining clip formed integral therewith by cutting the body of the strip, a 40 coupling-strip of flexible material attached to said strip of stiff material, a sheet of carbon-paper fastened at one of its ends to said flexible coupling-strip, and a protecting-sheet also fastened at one of its ends to said flexible 45 coupling-strip substantially in the manner and for the purpose described.

2. As an article of manufacture a copying device consisting of a strip of stiff material having a paper-retaining clip formed integral 50 therewith by cutting the body of the strip, a sheet of carbon-paper connected at one of its ends to said strip of stiff material and a protecting-sheet also connected at one of its ends to said strip of stiff material above the connected edge of the carbon-sheet for the purpose and substantially in the manner set forth.

3. As an article of manufacture a copying device consisting of a strip of stiff material having a paper-retaining clip formed integral 60 therewith by cutting the body of the strip, said strip of stiffening material being also formed with rearwardly-projecting tongues for insertion between the sheets of a book or pad as set forth, in combination with a sheet 65 of carbon-paper fastened at one of its ends to said strip of stiff material, as and for the purpose described.

FRANZ A. BARTELMEZ.
